Patented Aug. 18, 1959

185,941

MASSAGE TABLE AND VIBRATOR COMBINATION

Sammy Davis, Glendale, and Wayne C. Shank, Sherman Oaks, Calif.; said Shank assignor to said Davis

Application February 11, 1957, Serial No. 44,836

Term of patent 14 years

(Cl. D83—1)

Fig. 1.

Fig. 2.

Fig. 3.

Fig. 1 is a perspective view of a massage table and vibrator combination embodying our new design;

Fig. 2 is a rear elevational view thereof; and

Fig. 3 is a top plan view thereof, the broken line showing of the table being omitted for convenience of illustration.

The essential features of the design reside in the portion shown in full lines.

We claim:

The ornamental design for a massage table and vibrator combination, as shown and described.
